BENJAMIN H. KENNEDY AND DEWEY M. KENNEDY, OF ROCHESTER, NEW YORK.

INFANT'S BATHING APPARATUS.

Application filed July 23, 1923. Serial No. 653,137.

Our present invention relates to bathing apparatus and more particularly to bath tubs of a nature particularly adapted to bathing infants and it has for its object to provide a simple, inexpensive and convenient device of this nature having combined therewith a dressing table upon which the infant may be dried and dressed after the bath. The improvements are directed in part toward folding features of the tub and dressing table whereby the whole apparatus may be folded or the dressing table usually manipulated between operative and inoperative positions to give free access to either the tub or the dressing table as desired. To these and other ends the invention resides in certain improvements and combinations of parts all as will be hereinafter more fully described, the novel features being pointed out in the claims at the end of the specification.

In the drawings:

Figure 1 is a front view of a bathing apparatus constructed in accordance with and illustrating one embodiment of our invention; 25 the same being extended for use and the dressing table being in its upper operative position;

Figure 2 is an end view of the apparatus completely folded; 30 Figure 3 is an end view with the tub ready for use but the dressing table folded to inoperative position;

Figure 4 is a front view of the dressing table in folded position showing the under side 35 thereof, the view being in section through the support on the line 4—4 of Figure 3;

Figure 5 is an enlarged detail view of a latch for holding the device folded;

Figure 6 is an enlarged fragmentary trans- 40 verse sectional view through the apparatus with the dressing table in its lower operative position;

Figure 7 is a similar view with the dressing table in its upper operative position and

Figure 8 is a transverse sectional view similar to Figure 6 but showing a modified mounting of the dressing table permitting only one operative position thereof.

Similar reference numerals throughout the 50 several views indicate the same parts.

Our improved tub and dressing table preferably comprises a folding support upon which a flexible collapsible tub is carried in the manner of a camp stool seat. A dressing 55 table occupies a vertical folded position at one side of the tub and support when either

folded or extended and allows full access to the tub in the lateral position. After the baby is bathed the dressing table is drawn up to an operative position overlying the tub either 60 directly on the latter or elevated to a second level where its use is more convenient to a person standing instead of sitting.

Referring more particularly to the drawings, 1 and 2 designate a pair of crossed legs 65 at each end of the apparatus pivoted together at 3. Front and rear rails 4 and 5 connect the upper ends of corresponding legs of the pairs and hung between these rails is the collapsible tub 6 preferably composed of rubber 70 cloth or similar material so that it is normally stretched to an extended operative position by the spreading of the legs and limits such movement of the latter. When the device is folded as in Figure 2 the legs are closed together and the tub collapses between them. Lower rails 7 also connecting corresponding 75 legs are thus brought together and hook 8 pivoted on one is engaged with a button 9 on the other to maintain the folded position.

Supported at the front of the tub is a soap tray 10 preferably of similar material and supported between rail 4 and a swinging bail 11 pivoted between the legs 1 to move to the folded position of Figure 2, stops 12 being 80 provided to define its operative position.

The dressing table preferably consists of a rectangular frame 13 having canvas or other soft fabric 14 stretched across it. The end rails of the frame are slotted at 15 to receive 85 the connecting bar 16 of a yoke 18 having its ends pivoted at 19 in extensions 20 of the legs 2 at the back of the tub whereby the dressing table may slide upon the cross bar 16 forwardly and rearwardly and also vertically 90 behind the tub. Therefore, after the tub has been used in the position of Figure 3 and the dressing table is in the position there shown, when it is desired to bring the dressing table into use it is brought into the horizontal position of Figure 6 with an upward, forward sliding and pivotal motion so that it rests on the front on the front rail 4 and at the rear either upon the rear rail 5 or the bar 16. Catch pins 21 on the front rail of the dressing 95 table prevent it from moving rearwardly and becoming displaced.

As before stated, provision is also made for supporting the dressing table in a relatively elevated operative position suitable for use 100 when the attendant is standing. For this purpose the frame 13 is provided with two

folding legs 22 pivoted in the inner sides thereof at 23 and preferably consisting of yoke shaped members having a connecting and supporting bar 24 adapted to rest upon the rails 4 and 5 as shown in Figure 7, and having their ends bent at right angles to take the pivotal bearing in the dressing table frame as shown. These legs fold inwardly in the present instance and as the dressing table 10 is raised from the position of Figure 6 they fold by gravity to the position of Figure 7 except that it is thereafter desirable to spread them slightly as shown in Figure 1 for which purpose their pivots are arranged so close to the end rails of the dressing table frame as to cause the latter to act as stops limiting the spreading movement the purpose of which is of course to give added stability. The extensions 20 also prevent the dressing table 20 ports from moving laterally off of the tub.

The bars 24 of the legs are below the bar 16 of the supporting and guiding yoke 18 and when the dressing table is raised the bar 16 and the entire yoke swings upwardly from the position of Figure 6 to that of Figure 7.

To fold the table again, it is only necessary to drop the legs 22 whereupon the yoke 18 swings downwardly and guides it to either its lower operative position or, by a continued 30 motion, assists it to its complete folded position of Figure 3.

At the rear of the dressing table we prefer to provide a folding screen 25 that performs both the function of partially protecting the infant from drafts and providing convenient means for the reception of articles used in bathing and dressing the child. For instance in the present showing, it carries a pin cushion 26 and pockets 27. These, together 40 with the screen itself may be of cretonne or similar material stretched on a wire yoke 28 having offset ends 29 driven into the outer sides of the frame 13 to form pivots as shown in Figures 2 and 3 whereby the screen may 45 be swung from the erect position of Figure 6 and Figure 1 to the folded position of Figures 2 and 3 flat against the table. To hold it folded as in the figures a strap 30 may be provided at one edge of the dressing table co-operating with a buckle 31 on the screen 50 which strap is loosened when the screen is erected.

In Figure 8 we have shown so much of the construction as is required when only one 55 and that the lower position of the dressing table is desired. The extension 20 of the rear leg 21 is omitted and the yoke 18^a is pivoted at 19^a below the tub rail 5 instead of above it. Thus, the yoke 18^a is in a raised position when 60 the dressing table is in operative position as shown in Figure 8, though when folded back the guiding yoke occupies a similar pendant position.

Referring to Figure 7, rearward movement 65 of the dressing table in its raised position is

prevented by fingers 32 extended downwardly from the legs 22 at the front ends of the supporting bars 24 thereof so as to engage over the front of the rail 4.

We claim as our invention:

1. The combination with a support and a bath tub carried thereby, of a dressing table having an operative position overlying the tub and a vertical folded position at one side thereof, one of said parts being provided with a swinging yoke and the other with a guideway with which the yoke cooperates to effect a combined sliding and pivotal movement of the dressing table from one position to the other. 70

2. The combination with a support and a bath tub carried thereby, of a dressing table embodying a frame having slots in opposite rails thereof and adapted to assume an operative position overlying the tub or a vertical 75 folded position at one side thereof, and a yoke pivoted to the support and extending through the slots to effect a combined sliding and pivotal movement of the dressing table from one position to the other. 80

3. The combination with a support and a bath tub carried thereby, of a dressing table having an operative position overlying the tub and a vertical folded position at one side thereof, said dressing table being provided with a guideway and a swinging member pivoted to the support and upon which the dressing table is pivotally and slidably movable between its said two positions. 90

4. The combination with a support and a 100 bath tub carried thereby, the support at one side of the bath tub being extended above the rim of the latter, of a dressing table having an operative position overlying the tub and a vertical folded position at one side thereof, 105 said dressing table being provided with a guideway and a swinging member pivoted to the extension of the support above the tub upon which swinging member the dressing table is pivotally and slidably movable between its said positions. 110

5. The combination with a support and a bath tub carried thereby, the support at one side of the bath tub being extended above the rim of the latter, of a dressing table having 115 an operative position overlying the tub and a vertical folded position at one side thereof, said dressing table being provided with a guideway, a swinging member pivoted to the extension of the support above the tub upon 120 which swinging member the dressing table is pivotally and slidably movable between its said positions, and means for supporting the dressing table at another relatively elevated position on the tub. 125

6. The combination with a support and a bath tub carried thereby, the support at one side of the bath tub being extended above the rim of the latter, of a dressing table having 130 an operative position overlying the tub and a

- vertical folded position at one side thereof, said dressing table being provided with a guideway, a swinging member pivoted to the extension of the support above the tub upon 5 which swinging member the dressing table is pivotally and slidably movable between its said positions, and a pair of folding legs on the dressing table for supporting the latter at another relatively elevated position on the 10 tub.
7. The combination with a support and a bath tub carried thereby, the support embodying pairs of crossed legs corresponding elements of which are extended above the tub 15 at one side, of a dressing table having an operative position overlying and resting upon the tub and a vertical folded position at one side thereof, said dressing table being provided with a guideway, a swinging yoke mounted on the extensions of the legs and slidable in the guideway of the dressing table to permit the latter to move between its two said po-
- sitions with a combined sliding and pivotal motion and folded legs pivoted to the dressing table to rest when extended upon the tub 25 and support the dressing table in another relatively elevated position above the tub.
8. The combination with a collapsible support and a collapsible tub carried thereby, of an overlying dressing table supported on the latter and movable to a folded position against the tub and support when collapsed, a screen pivoted to one side of the dressing table to fold flat against the same and means for securing the screen in its folded position. 30
9. The combination with a collapsible support and a collapsible tub carried thereby, of an overlying dressing table supported on the latter and movable to a folded position against the tub and support when collapsed, 40 and a screen pivoted to one side of the dressing table to fold flat against the same.
